UNITED STATES PATENT OFFICE.

CLARENCE M. BROWN, OF MINDEN, LOUISIANA.

AIR-HOSE COUPLING.

1,340,820.

Specification of Letters Patent. Patented May 18, 1920.

Application filed November 27, 1918. Serial No. 264,382.

To all whom it may concern:

Be it known that I, CLARENCE M. BROWN, a citizen of the United States of America, residing at Minden, in the parish of Webster and State of Louisiana, have invented new and useful Improvements in Air-Hose Couplings, of which the following is a specification.

The purpose of the invention is to provide 10 a coupling for air brake hose which will act automatically to couple and uncouple the same when cars are being coupled and uncoupled. To this end the invention comprises a pair of longitudinal tubular members 15 for mounting below the draft bar of a car, the tubular members being mounted in suitable supports with reference to which they are permitted a certain amount of longitudinal movement and a certain amount 20 of up and down and lateral movements at their free ends. The tubular members terminate at their free ends in Y shaped heads the legs or arms of which lie in diagonally disposed planes so that the head carried by 25 the tubular member on one car may be in a position to connect with the similar head on another car irrespective of whether the first said car is turned end for end. The longitudinal movement of which the tubular 30 members are capable is obtained against the pressure of resilient means whereby connecting heads are always retained in coupled position.

A further purpose of the invention is to 35 provide a device of the character mentioned above which is simple in construction, durable and effective in operation and inexpensive to manufacture.

Other and further purposes appear in the 40 following description wherein the device is set forth in detail.

To the exact construction in which it is shown and described, the invention is not to be restricted. The right is reserved to 45 make such changes or alterations as the actual reduction to practice may suggest, provided such changes or alterations do not deviate from the scope of the annexed claims.

50 In the accompanying drawings:

Figure 1 is a view in side elevation showing the coupled ends of a pair of cars, the improved device being shown in coupled position.

55 Fig. 2 is a section on the line 2—2 of Fig. 1.

Fig. 3 is a section on the line 3—3 of Fig. 1.

Fig. 4 is a section on the line 4—4 of Fig. 1. 60

Fig. 5 is a section on the line 5—5 of Fig. 1.

Referring to the drawings, there are shown the draft bars 1 carrying the couplings 2 by which the two cars are coupled 65 together. The improved air hose accompanying the device is carried below the draft bar 1 and comprise an L shaped bracket 3 secured to the draft bar. This L shaped bracket is formed in its depending 70 leg with a hole through which the tubular member 4 passes the latter connecting at one end with a flexible tubular member or hose 5 which is connected with the air system of the car on which the improved device 75 is used. The tubular member 4 at its other end connects with a Y shaped coupling head 6 whose leg 7 is square in cross-section and made hollow. A spiral spring 8 surrounds the tubular member 4 and is compressed be- 80 tween the end of the leg of the coupling head and the depending leg of the bracket 3, this spring tending normally to force the coupling head away from the bracket 3.

The coupling head 6 is formed with two 85 diverging arms 9 which together with the leg 7 give the coupling head the Y shape referred to. The bore of the leg 7 opens in the crotch formed where the two arms 9 connect with the leg and in this crotch there is 90 set a resilient washer, made preferably of rubber.

It will be observed that the arms 9 lie in a diagonally disposed plane, thus making it possible for coupling heads of different cars 95 to engage irrespective of whether one of the cars is turned end for end.

In order that the coupling head may be permitted longitudinal movement as well as up and down and lateral movement, the leg 100 of the coupling head is slidably mounted in a block 11 formed with a square hole so positioned that it retains the coupling head against angular movement and thus retains the arm of the coupling head in the diagonal 105 plane referred to. The block 11 is slidably mounted in a frame 12 with respect to which it may move when the coupling head is moved laterally. The frame 12 is in turn mounted in a frame 14 with respect to which 110 it may move when the coupling head is moved up and down or raised and lowered.

as it is due to irregularities in the road bed. The frame 14 is secured on the under face of the draft bar 1. The bracket 3 is provided with no moving part but the hole 5 formed therein is of sufficient size to permit the tubular member 4 to move freely therein, so that when the coupling head is subject to up and down or lateral movement such movements are effected with the point of 10 combination between the tubular member 4 and bracket 3 as a pivot.

It is obvious that when two cars equipped with the two coupling heads are connected together by means of their couplings 2, the 15 coupling heads 6 will be made to connect, the arms 9 of the one straddling the other at the crotch of the latter, and the connection being maintained firm by the pressure of the springs 8. With the improved construction 20 it is intended that the valves used in connection with the air brake system of individual cars shall be placed adjacent the sides of the latter so that they may be operated without requiring a brakeman to go 25 between the cars. With the present invention they are positioned as stated and are included in the tubular connections 5. Thus when the air systems of two cars are coupled by means of the improved device, these 30 valves are opened without having to enter between cars and thereby the air brake system of the train is made continuous, the air hose coupling remaining in coupled position as long as the draft couplings are in such 35 position.

It is believed that the foregoing description, when taken in conjunction with the accompanying drawings gives a full, clear and comprehensive understanding of the invention and further description is, therefore, omitted.

The invention having been described, what is claimed as new and useful is:

1. In a coupling for air hose, a Y-shaped 45 coupling head formed with a hollow leg, the bore of which opens in the crotch be-

tween the diverging arms of the head, a tubular member connecting with the coupling head at the end of the leg remote from the arms, an L-shaped bracket for attachment to the draft bar of a car, one leg of the said L-shaped bracket being formed with a hole through which the tubular member slidably passes, a spring in surrounding relation to the tubular member and compressed between the bracket and that end of the leg of the coupling head with which the tubular member engages, a block with which the leg of the coupling head slidably engages but with respect to which it is secured against angular movement, a frame 5 slidably supporting the block to permit lateral movement of the coupling head, and a second frame having means for attachment to the draft bar of a car and slidably supporting the first said frame to permit movement of the latter when up and down movement is imparted to the coupling head.

2. In a coupling for air brake hose, a Y-shaped coupling head formed with a leg 7 polygonal in cross-section and bored throughout its length, connections whereby the leg of the coupling head may be connected to the air brake system of a car, a block formed with a hole corresponding in shape to the cross-sectional shape of the leg so that the latter may slidably engage the block and be secured against angular movement with respect thereto, a frame 7 slidably supporting the block to permit lateral movement of the coupling head, a second frame having means for attachment to the draft bar of a car and slidably supporting the first said frame to permit movement of the latter when up and down movement is imparted to the coupling head, and resilient means tending normally to force the leg of the coupling head in the direction of the length of the leg.

In testimony whereof I affix my signature.

CLARENCE M. BROWN.
